(57) **CLAIM**

The ornamental design for a litter receptacle, as shown and described.

DESCRIPTION

FIG. 1 is a top and front perspective view of a litter receptacle showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a top and front perspective view thereof, showing my new design in a second position in which a foot lever is depressed and a litter-receiving drawer is opened; and, FIG. 9 is a top and front perspective view thereof, showing my new design in a third position in which an access door is partially opened.

The broken lines in the drawings illustrate portions of the litter receptacle that form no part of the claimed design.
